(57) **CLAIM**

The ornamental design for an exercise ball, as shown and described.

DESCRIPTION

FIG. 1 is a right-side perspective view of the exercise ball of my design;

FIG. 2 is a front view thereof;

FIG. 3 is a top view thereof;

FIG. 4 is a bottom view thereof;

FIG. 5 is a right-side view thereof;

FIG. 6 is a left-side view thereof;

FIG. 7 is a right-side perspective view thereof showing the handle in an alternate position;

FIG. 8 is a right-side view thereof showing the handle in an alternate position; and,

FIG. 9 is a front view thereof showing the handles in an alternate position.

The broken lines in the drawings form no part of the claimed design.
